UNITED STATES PATENT OFFICE.

RALPH ROSE AND NICHOLAS F. CIMAGLIA, OF MOUNT VERNON, NEW YORK.

SPLICING-EAR FOR OVERHEAD TROLLEY-WIRES.

1,377,972.

Specification of Letters Patent. Patented May 10, 1921.

Application filed July 16, 1919. Serial No. 311,341.

To all whom it may concern:

Be it known that we, RALPH ROSE, a citizen of the United States, and NICHOLAS F. CIMAGLIA, a citizen of the United States, 5 residing in the city of Mount Vernon, in the county of Westchester and State of New York, have invented a new and Improved Splicing-Ear for Overhead Trolley-Wires, of which the following is a specification.

10 The splice ears in use at the present time are unsatisfactory, as the edges which come in contact with the riding wheel on the trolley pole wear out very readily, and consequently require frequent renewals. The 15 object of this invention is to provide a splice ear with a removable wearing edge which can be replaced when worn out without affecting the former. Another object of this invention is to provide a device which can be 20 used either as a splicing ear or as a supporting member at the places where the trolley wire is held by the cross wires between the two poles placed along the road at frequent intervals.

25 We obtain this object by means of the device fully described herein and illustrated in the accompanying drawings forming a part of this specification.

One of the many features and advantages 30 of this device is that the riding trolley wheel passes over a convex surface on the under side of the guide piece instead of wearing against the edges of the ear, encircling the wire, which is the case in existing devices.

35 Another feature of our device is that the same ear can be used for either splicing or supporting the trolley wire and also that it can be used for several thicknesses of wire. An additional feature, is that it can also be 40 used to connect the feed wire whenever it is necessary. Another very important feature of our device is that the ear can be connected to the supporting cross wire at the supporting poles without the use of screws, by 45 merely engaging it with the supporting piece, which is in turn held by the cross wires.

Referring to the drawings, Figure 1 is a 50 side view of the ear frame; Fig. 2 is a side view of the protecting plate, or wearing edge; Fig. 3 is a front view of the ear supporting piece; Fig. 4 is a side view of the supporting piece; Fig. 5 is a section taken on line 5—5 of Fig. 1; Fig. 6 is an end view of the protecting plate shown in Fig. 2, Fig. 7 is a side 55 view of the ear attached to the supporting

piece, with the protecting plate in position; Fig. 8 is an end view of the device assembled; Fig. 9 is a top view of the device assembled; Fig. 10 is a section taken on line 10—10 60 of Fig. 8; Fig. 11 is a bottom view of the device looking in the direction of line 11—11 of Fig. 7 with a portion of the plate broken away to show the interior; Figs. 12, 13, and 14, are sections taken on lines 12—12, 13—13 65 and 14—14 respectively of Fig. 1; Fig. 15 is section taken on line 15—15 of Fig. 9, showing the device used for continuous wire support and showing a feed wire connection, Fig. 16 is a section similar to Fig. 15, 70 showing the device used as a splice; Fig. 17 is a perspective elevation of the device completely assembled, with the feed wire in place; Fig. 18 is a top view of the protecting plate before it is attached to the ear, looking 75 in the direction of line 18—18 of Fig. 2; Fig. 19 is a top view of the ear looking in the direction of 19—19, of Fig. 1, and Fig. 20 is an elevation of the device shown in perspective, when used as splicing ear. 80

Referring to the drawings, the main member 1, the outline of which is shown in Fig. 1 has its side sloping as shown at 4 in Figs. 5, 12, 13 or 14 and is provided with a semi-circular groove 2 at the bottom running for 85 the full length of the member into which the wire to be spliced or supported is adapted to fit. The member 1 is also provided with the vertical passages 5 and 6 through which the ends of the wires 7 and 8, which are to be 90 spliced, are passed through, and bent over, as shown in Figs. 16 and 20. If the ear 1 is used for supporting the wire, instead of splicing the wire 9 is placed within the groove 2 for its full length as is clearly shown 95 in Fig. 15. In order to properly anchor the wire and to provide a suitable wearing edge for the riding wheel on the trolley pole, the following construction is provided: The protecting member 10, preferably made 100 of a malleable alloy of copper, and U-shaped as shown in Fig. 6, and otherwise shaped as shown in Figs. 2 and 18, is provided with the bolt holes 11, 12 and 13 in its sides and is adapted to fit over the member 1. The 105 member 10 is fixed to the ear 1 by means of the bolts or screws 14, 15 and 16. The bolt 15 passes through the slotted hole 3 in the member 1. When the bolts 14, 15 and 16 are tightened, the sides of the member 10 are 110 brought to bear against the inclined surfaces 4 of the member 1 and thereby the member

10 is very firmly held against the member 1 as is clearly shown in Fig. 8 and in plan in Fig. 9. In order to provide a firm grip on the ends of the wires 7 and 8, the member 10 is provided at the sides near the bottom with the projecting teeth 17 which are adapted to grip the wire and thereby prevent the latter from pulling out. In order to have the inner surface of the member 10 fit snugly 10 against the wire, the slotted hole 3 in the member 1 is provided, which permits the pressing of the member 10 against the wire before the bolts 14, 15 and 16 are tightened. To provide smooth riding for the trolley 15 wheel over the edge of the member 10, the thickness of the bottom of the U portion is reduced near the ends as is shown in Figs. 6, 15 and 16 so that its surface slopes gradually toward the center where it is thicker and 20 is then reduced in thickness gradually as it approaches the other end. Similarly the width of the member 10 is less at the ends than at the center, so that the riding trolley wheel can get over it easily.

25 When the ear is used for splicing purposes, as shown in Fig. 16, it is found desirable to insert a short piece of wire 18 in order to fill in the gap between the wires 7 and 8 and thereby prevent the bottom of member 10 from flattening out when the trolley wheel passes over it. When it is desired to connect a feed wire 29 to the ear 1, the passage 5 or 6 may be used for that purpose, in which case the end of the wire 35 19 is inserted therein and is held by means of a screw 28.

The member 1 is connected to the supporting member 19 in the following manner: The supporting member 19, being in 40 general shape similar to those in use in existing devices, is supported between the poles in the roadway by means of the cable 20. The bolt 21 having the two projecting pins 22 and 23 at the end thereof is fixed 45 within the interior of the supporting member 19 and is insulated therefrom by means of the insulating material 24. The member 1 is provided with a cylindrical hole 25 at the center thereof adapted to receive the bolt 50 21 and a slot 27 into which the pins 22 and 23 projecting from the bolt 21 are adapted to enter. At the bottom of said slot 27 is a cylindrical chamber 26 which is concentric with the hole 25 whereby the pin 21 can be 55 rotated within the hole 25, the pins 22 and 23 engaging with the top and bottom of said chamber 26.

It will now be evident that the device is 60 supported in the following manner: The member 19 is held in place by means of the cable 20 suspended between the two poles in the roadway, with the bolt 21 projecting from the under side thereof. The ear 1 is attached in position by bringing the hole 25 over the bolt 21, the pins 22 and 23

meanwhile entering the slot 27 until they get within the chamber 26, after which the member 1 is rotated through an angle of 90 degrees. The device is then ready to have the trolley wire attached thereto.

70

Having thus described our invention, we claim as new and wish to secure by Letters Patent:

1. In a device of the character described, the combination of a splicing member having bulged sides, adapted to have the ends of the trolley wire attached thereto, and a U-shaped guide piece removably attached to said splicing member, adapted to fit over the ends of the trolley wire and to have its sides 75 bear against the sides of said splicing member.

2. In a device of the character described, the combination of a splicing member, having its sides bulged near the bottom, adapted 80 to have the ends of trolley wires attached thereto, and a U shaped guide piece removably attached to said splicing member adapted to fit over the ends of the trolley wires and to have its sides bear against the 85 bulging sides of said splicing member.

3. In a device of the character described, the combination of a splicing member, having bulged sides, adapted to have the ends of the trolley wire attached thereto, and a U 95 shaped guide piece removably attached to said splicing member, adapted to fit over the ends of the trolley wire and to have its sides bear against the bulging sides of said splicing member, the under side of said 100 guide piece being shaped to fit within the groove of the traveling trolley wheel.

4. In a device of the character described, the combination of a wire supporting member, having bulging sides, and a U shaped 105 guide piece vertically adjustable and removably attachable to said supporting member, adapted to cover the trolley wire attached to said supporting member and adapted to have its sides bear against the bulging sides 110 of said supporting member.

5. In a device of the character described, the combination of a splicing member having a groove at the under side thereof and openings through the body thereof, adapted 115 to have the ends of trolley wires pass therethrough, the sides of said splicing member being bulged near the bottom, and a U shaped guide piece removably attached to said splicing member, adapted to fit over the ends of the trolley wire and to have its sides bear against the bulging sides of said splicing member, the under side of said 120 guide piece being shaped to fit within the groove of the traveling trolley wheel.

125

6. In a device of the character described, the combination of a wire supporting member having bulging sides, and a protecting guide piece vertically adjustable and removably attachable to said supporting member, 130

adapted to cover the trolley wire attached to said supporting member, and adapted to have its sides bear against the bulging sides of said supporting member.

5 7. In a device of the character described, the combination of a splicing member having a groove at the under side thereof, openings through the body thereof, and its sides bulged near the bottom, adapted to 10 have the ends of the trolley wire pass therethrough, a U shaped guide piece removably attachable to said splicing member, having a roughened interior surface, adapted to fit over the ends of the wire and to hold them 15 in position.

8. In a device of the character described, the combination of a splicing member having a cross section tapering from a point near the bottom toward the center, adapted to have the ends of the trolley wire attached thereto, and a U-shaped guide piece removably attached to said splicing member, adapted to fit over the ends of the trolley wire and to have its sides bear against the tapering sides of said splicing member. 20 25

Signed at Mount Vernon, in the county of Westchester, State and city of New York, this 10th day of July, 1919.

RALPH ROSE.
NICHOLAS F. CIMAGLIA.
